Lester Witterhofer

UNITED STATES PATENT OFFICE.

HERBERT ABRAHAM, OF NEW YORK, N. Y., ASSIGNOR TO THE STANDARD PAINT COMPANY, A CORPORATION OF NEW JERSEY.

STRIP-SHINGLE.

1,326,899.

Specification of Letters Patent.

Patented Jan. 6, 1920.

Application filed October 18, 1918. Serial No. 258,703.

To all whom it may concern:

Be it known that I, HERBERT ABRAHAM, a citizen of the United States, residing at the city, county, and State of New York, have invented certain new and useful Improvements in Strip-Shingles, of which the following is a specification.

My invention relates to strip shingles of prepared roofing.

10 The principal object of the invention is to produce strip shingles of such form that a given area of roof deck can be covered and made watertight with a smaller quantity of material than has heretofore been required.

15 Another object is to produce a shingle strip having a plurality of nailing tabs along its upper edge.

20 A still further object is to cut the strips so that the cutaway portions of one row of shingles form the nailing tabs of the next lower row.

This invention pertains particularly to an improvement in strip shingles of the type shown and described in Patent No. 1,150,298, 25 issued August 17th, 1915, to F. C. Overbury. With the shingle strip of that patent, having straight upper edges, it requires approximately 250 square feet of shingle surface to cover 100 square feet of roof deck, 30 whereas with shingle strips made according to my invention, that is, having nailing tabs along their upper edges, the same area of roof deck can be covered and rendered watertight with approximately 200 square feet 35 of shingle surface.

In the accompanying drawings,

Figure 1 is a plan view of a strip shingle embodying my invention;

40 Fig. 2 is a view of a fragment of a sheet of prepared roofing indicating the method of manufacturing the shingle strips;

Fig. 3 is a section of laid strip shingles and,

45 Fig. 4 is a modification showing a strip shingle having semi-circular shaped nailing tabs.

According to my invention, I take a sheet of prepared roofing and cut out a plurality of small oblong shaped openings 1 in rows 50 across the sheet, the openings in any one row being disposed midway between the openings in the next upper and lower rows. In the completed strip shingles, shown in Figs. 1 and 4, these openings form the slits 55 between adjacent shingles. The sheet is then

severed along wavy-like lines 2, extending transversely along the sheet as shown in Fig. 2. This produces a multiple shingle strip having a series of nailing tabs 3 along its upper edge, and having its lower edge 60 formed of a series of straight lines extending parallel to the major-axis of the strip and separated by cut-out portions which substantially correspond in shape to the nailing tabs, said nailing tabs being disposed in staggered relation to the cut-out portions of the lower edge. The strips are generally cut into blocks of four shingles each, as indicated in Fig. 2, to form the completed article shown in Figs. 1 and 4. It will be seen, 65 by reference to Fig. 2, that the tabs 3 of any one strip are formed of material cut out of the indentations of the next higher strip. In this way the shingle strips are produced without any loss of material other than that 70 caused by the cutting out of the openings 1 and the necessary trimming at the top and bottom of the sheet.

By varying the character of the cutting line 2 the tabs 3 may be made of other than 80 triangular shape, for example, they may be of semi-circular shape, as shown in Fig. 4.

Having reference to Fig. 3, in which I have shown a section of strip shingles, laid in the usual manner, that is with the shingles of one course covering the joints of the other, it will be seen that by provision of the nailing tabs 3 I effect a considerable saving of shingle material between nailing points over the old type of shingle strip having a straight upper edge; at the same time the same amount of protection against leakage at the joints between adjacent strips is provided as with the old type of shingle strip. 95

What I claim is:

A multiple shingle-strip, having spaced nailing tabs along its upper edge, and having its lower edge formed of a series of straight lines extending parallel to the major axis of the strip, with intervening cut-out portions corresponding substantially in shape to the nailing tabs and disposed in staggered relation thereto, whereby, when the strips are laid as described, not more 100 than two square feet of shingle material are required to waterproof each square foot of roof surface. 105

HERBERT ABRAHAM.
